(57) **CLAIM**

The ornamental design for a earring, as shown and described.

DESCRIPTION

FIG. 1 is a front elevational view of my new earring design;
FIG. 2 is a rear elevational view thereof;
FIG. 3 is a left side view thereof; the right side view being a mirror image thereof;
FIG. 4 is a top plan view thereof;
FIG. 5 is a bottom plan view thereof;
FIG. 6 is a front elevational view of a second embodiment of my new earring design;
FIG. 7 is a rear plan view thereof;
FIG. 8 is a left side view thereof; the right side view being a mirror image thereof;
FIG. 9 is a top plan view thereof;
FIG. 10 is a bottom plan view thereof;
FIG. 11 is a front elevational view of a third embodiment of my new earring design;
FIG. 12 is a rear elevational view thereof;
FIG. 13 is a left side view thereof; the right side view being a mirror image thereof;
FIG. 14 is a top plan view thereof; and,
FIG. 15 is a bottom plan view thereof.
The darker shaded gemstones in FIGS. 1, 4-6, 9-11 and 14-15 illustrate gemstones of a contrasting color.
